UNITED STATES PATENT OFFICE.

WILLIAM T. ROOT, OF GENEVA, NEW YORK.

IMPROVED DOOR-SPRING.

Specification forming part of Letters Patent No. 39,308, dated July 21, 1863; antedated March 7, 1863.

To all whom it may concern:

Be it known that I, WILLIAM T. ROOT, of Geneva, in the county of Ontario and State of New York, have invented certain new and useful Improvements in Spring Attachments for Closing Doors, Gates, &c.; and I do hereby declare that the following is a full and exact description thereof, reference being had to the accompanying drawings, making part of this specification.

Figure 1 is a plan of my improved attachment connected with a door and its seat, the door being represented as partly open; Fig. 2, an edge view of the spring attachment; Fig. 3, a perspective view of the supporting or spring portion of the case detached from its fellow; Fig. 4, a perspective view of the drum or band portion of the case also detached from its fellow; Figs. 5 and 6, horizontal sections of the case with the mainspring removed, in the plane of the red line, Fig. 2, the former showing the band or strap entirely wound up and the latter as entirely unwound.

Like letters of reference indicate corresponding parts in all the figures.

My improved device is of that character in which a case or drum is used attached to the seat or casing of the door, having winding on its periphery a band whose outer extremity is connected with the door, and which is actuated by means of a mainspring within that coils or winds up when the door is opened, but uncoils to produce the reaction in closing the door. The case is composed of two parts, A and B, being respectively provided with hollow cylindrical projections *a* and *b*, fitting one within the other, thus forming a drum for the band to wind on, and provided also with a rim or flange, *c*, at each side, of larger diameter, to guide the band and keep it in place, so as to wind on itself, as will presently be described. The part A which is the supporting portion rests on a bearing, C, substantially of the shape represented, having a base, from which projects vertically a cylindrical axis, *d*, of suitable length, passing through a central hole in the said part A, which turns around it, and is thus sustained in place. The bearing is secured to the wood-work by means of suit-

able lugs or flanges, *f f*, through which pass screws or nails. Within the cylindrical projection *a* of this part of the case rests a flat coiled spring, *I*, or its equivalent, one end being fastened at *g* to the axis and the other end at *h* to the side of the cylinder, as shown clearly in Fig. 3. Thus, as the case is turned in the direction of the arrow, the spring is wound up, and vice versa. This arrangement of the spring itself does not differ materially from other devices of this class. The other or band portion B of the case is also provided with a central hole for fitting over the axis *d*, and its cylinder is of just such size as to closely inclose and embrace that on the part A when in place, but still to allow each individual part of the case to turn free and independent of the other. In the edge or rim of the cylinder *b*, at equal distances apart, are made a suitable number of notches, *i i*, Fig. 4, and at the base of the cylinder *a* are made one, two, three, or more teeth, *k k*, Fig. 3, of corresponding shape, which fit into the notches when the parts are in place. The teeth point away from the direction of motion of the part A in winding up the spring, and consequently the notches point in the opposite direction. It is manifest that in turning the two parts of the case in opposite directions, or in turning one while the other is held stationary, that the spring *I* may be wound up to any degree of stiffness desired, and held there as the notches and teeth *i k* engage. It is only necessary to insure this engagement, or, in other words, prevent the teeth and notches from slipping. To accomplish this, I secure around the axis *d*, outside the case, an ordinary spiral spring, *l*, or its equivalent, Fig. 2, resting against a washer, *m*, which in turn is held in place and adjusted by means of an adjusting-screw, *n*, screwing to the axis in any convenient manner, being represented in the drawings as entering a hole, *o*, Fig. 3, in its end. It will be readily perceived, that as this screw is adjusted the spring *l* is made to press with a greater or less degree of force against the side of the case, thus, not only allowing the mainspring *I* to be wound up without difficulty, but also securely holding the two parts of the case

together. To the periphery of the outer cylinders, *b*, is secured, in any convenient manner, the end of a band or strap, *E*, the attachment in the drawings being a screw-head or projection, over which fits a hole made in the band, as indicated at *p*, Fig. 4. To accomplish the result I have in view, this band is made of considerable thickness — say about one-eighth of an inch, more or less — in a door-spring for a common door, and as a consequence it is necessarily made of leather, cloth, or some equivalent flexible material that will easily wind. To the outer extremity of the band is secured a spur or projection, *r*, conveniently constituting a portion of the metal that attaches to the door, extending outward sufficiently from the band to strike against a stop, *s*, formed by the lug or shoulder *f*, projecting so as to reach to the edge of the case and prevent the spur from being drawn through, as indicated most clearly in Fig. 5, which shows the spur fully drawn up to the stop. A stop is provided on each side of the case, so as to adapt the device to either right or left hand doors. It is apparent that if the outer end of the band is held stationary the mainspring may be wound up by turning the parts of the case in opposite directions, so as to give a greater or less degree of reaction, to adapt the device to doors of greater or less size or weight, for if the spring is already partially wound it will present a greater resistance in winding it still farther by opening the door than if it is perfectly unwound at first. The arrangement is thus perfectly adapted to closing either large or small doors or gates, saving the trouble of making different sizes for different uses. The notches and teeth *i k*, by being situated within the case, are in the most compact and least exposed condition, and do not interfere in the least with the perfect action of the device.

I am aware that a ratchet and pawl connected with the case have before been used for accomplishing an adjustment of the mainspring, but such I do not claim. In such an arrangement the cost is not only largely increased in the aggregate, but it renders the case unsightly and inconvenient. The greatest objection, however, is that by thus being exposed the device is extremely liable to accident, as a slight touch of any kind is sufficient to remove the small point of the pawl from its ratchet-tooth and let the spring free. The motion of the case or drum itself in opening the door is sufficient to frequently disarrange the parts, especially as there is no pressure on the pawl to keep it in place. I overcome this difficulty in the simplest and most effective manner, the constant pressure of the side spring, *l*, applying to the part *B* of the case, to keep it in place and holding the parts firmly together. The adjustment produced by the screw *n* insures any desired amount of press-

ure of the spring *l* so that in winding up the mainspring the parts *A B* may be loosened, so as to turn easily, and when the action is accomplished they may be adjusted firmly together, so that there can be no possible escape of the notches and teeth *i k*.

By the use of the thick flexible band or strap *E*, winding upon itself, in the narrow space inclosed between the rims or flanges *c c* of the case, I accomplish an effect that is very essential, and which is accomplished in other devices only by the use of a fusee-wheel. When the door first commences to open, the reaction required to close it is but very slight, but when fully open the reaction required is greatly increased. This is partially compensated for by the increased stiffness of the spring; but this is not sufficient, especially in heavy doors or gates. It is necessary to vary the size of the coil of band to accomplish this. Thus, when the door first commences to open, the band is fully wound up, presenting a large radius, as in Fig. 5; but when open, the band is unwound, presenting only a small radius, as in Fig. 6. This obviously varies the leverage, it being the greatest when the radius is the least, or when the door is open. This simple device accomplishes all that is accomplished by the use of a fusee-wheel, while great economy of cost and space are secured, and the band always works on the same plane at all times, while in a fusee-wheel it is constantly changing. By the use of the spur *r* and the stops *s s* the band is prevented from being drawn through and becoming unwound, and the spring broken or injured if it becomes detached from the door by accident or otherwise. By the employment of the stops on opposite sides the arrangement is adapted to use with right and left hand doors with the same effect. The spur and stop enable the device to be taken off the bracket or door in summer when the spring is not required, and also enables the springs to be packed for shipment without liability to injury or derangement of the parts.

I do not claim the use of a ratchet and pawl for adjusting the mainspring to different degrees of resistance; nor do I claim the use of a fusee-wheel for graduating the leverage on the door; but

What I claim as my invention, and desire to secure by Letters Patent, is —

1. The combination, with the parts *A B* of the case, provided with the notches and teeth *i k*, of the coiled spring *l*, or equivalent, and adjusting-screw *n*, for the purpose of adjusting the mainspring to greater or less degrees of resistance, and for holding the said parts of the case together, arranged and operating substantially as herein described.

2. The double stops *s s*, situated, respectively, on opposite sides of the drum, and forming a part of the support or bearing of the

same, in combination with the spur *r*, for the purpose of preventing the band from being drawn through, and for adapting the device to both right and left hand doors, as herein specified.

3. The special construction, arrangement, and combination of the whole device, consisting, essentially, of the case *A*, *B*, mainspring *I*, band *E*, spur and stops *r s*, side spring, *t*,

and adjusting screw *n*, substantially as herein set forth.

In witness whereof I have hereunto signed my name in the presence of two subscribing witnesses.

W. T. ROOT.
